[57] CLAIM

An ornamental design for a watch, as shown and described.

DESCRIPTION

FIG. 1 shows a front perspective view of the first embodiment of the watch of the invention;

FIG. 2 shows a top view thereof;

FIG. 3 shows a front view thereof;

FIG. 4 shows a left side view thereof (right side being a mirror image);

FIG. 5 shows a back view thereof;

FIG. 6 shows a bottom view thereof;

FIG. 7 shows a front perspective view of the second embodiment of the watch of the invention;

FIG. 8 shows a top view thereof;

FIG. 9 shows a front view thereof;

FIG. 10 shows a left side view thereof (right side being a mirror image);

FIG. 11 shows a back view thereof; and,

FIG. 12 shows a bottom view thereof.

The watch has two embodiments, one of a man's style watch and one of a woman's style watch.
